UNITED STATES PATENT OFFICE

2,045,280

NECKTIE CONSTRUCTION

William Mayer, New York, N. Y.

Application July 20, 1935, Serial No. 32,344

2 Claims. (Cl. 2—155)

My present invention relates generally to neckwear, and has particular reference to certain improvements in neckband portions.

A general object of the invention is to provide certain improvements of the character in which a neckband portion is composed of two sections adapted to be separably connected end to end.

One of the features of the invention lies in providing a pair of complementary fasteners on the ends of said sections, respectively, in combination with an extension flap on one of the sections adapted to overlie the area of juncture when the fasteners are connected.

Another feature of the invention lies in providing an open-ended pocket at the end of one of the sections, and mounting one of the complementary fasteners in said pocket in an improved manner.

A still further feature of the invention lies in forming such a pocket of the inner and outer plies of tie material, of which the neckband portion is composed; and in making the outer wall of the pocket longer than the inner wall so as to provide the extension flap hereinbefore referred to.

A still further feature of the invention lies in mounting one of the complementary fasteners within the pocket by securing it to a stretchable band whose inner end is secured to the inner end of the pocket.

I achieve the foregoing objects, and such other objects as may hereinafter appear or be pointed out, in the manner illustratively exemplified in the accompanying drawing, wherein—

Figure 1 is a perspective view of a necktie construction embodying the features of my present invention;

Figure 2 is an enlarged cross-sectional view taken substantially along the line 2—2 of Figure 1;

Figure 3 is an elevational view showing the neckband sections connected end to end;

Figure 4 is a cross-sectional view taken substantially along the line 4—4 of Figure 3; and

Figure 5 is a cross-sectional view taken substantially along the line 5—5 of Figure 3.

I have chosen to illustrate my present invention in connection with a so-called "ready-made bow tie", comprising the knot portion 10 and the two oppositely extending neckband portions 11 and 12. The neckband section 12, which I have illustrated, is of the adjustable variety whereby a portion 13 is doubled back upon the body of the section 12 and is provided with a

hook 14 adapted to enter any selected one of a series of perforations 15. A loop 16 is carried by the section 12 and constitutes one of the complementary fasteners for securing this section in a separable manner to the section 11 when the tie is to be worn. Accordingly, the portion of the section 12 to which the loop 16 is applied may be deemed to be the "end" of the section 12, as this term is used herein and in the appended claims. In other words, it is immaterial to the present invention whether the section 12 is of adjustable length or not. It is equally immaterial whether the tie portion is a bow or a four-in-hand type of knot; and, furthermore, it is immaterial whether the necktie construction is of the ready-made variety or the untied variety.

The essential elements of the present construction, so far as the present invention is concerned, consist of the two separate neckband sections 11 and 12 adapted to be separably connected in end-to-end relation. As already mentioned, the section 12 has at its end a fastener element consisting of the loop 16. The other section 11 has a complementary fastener in the form of a hook 17 which is adapted to engage separably with the midportion of the loop 16.

In accordance with my invention, the hook 17 is mounted on the end of a stretchable band 18, which may be of elastic or the like, the inner end of this band being secured, as at 19, to the inner end of a pocket formed on the section 11. This pocket has an outer wall 20 and an inner wall 21, and in accordance with my invention, the outer wall 20 is formed on, and is preferably integral with, the outer ply 22 of the neckband construction. Similarly, the inner wall 21 is formed on, and is preferably integral with, the inner ply 23 of the neckband construction. The plies 22 and 23 are stitched together at their longitudinal edges, and the walls 20 and 21 of the pocket are similarly stitched together, as shown most clearly at the points 24 in Figure 5.

The free end 25 of the inner wall 21 is preferably doubled back upon itself, as shown most clearly in Figures 2 and 4, though it need not be stitched down. The free end 26 of the outer wall 20 is similarly doubled back upon itself and is preferably stitched down as at 27.

In accordance with my invention, the outer wall 20 of the pocket is longer than the inner wall 21, whereby an extension flap is provided by the excess length. This flap as a whole is designated by the reference numeral 28, and it will be observed that this flap overlies the area

of juncture when the fasteners 16 and 17 are connected. This is shown most clearly in Figures 3 and 4, and the advantage lies in the fact that the fasteners are concealed and covered, thereby improving the efficiency with which the neckband may be disposed in association with a collar. In the case of a tie which is used for full-dress wear, the concealment is of particular advantage because it hides from the casual observer the fact that the wearer is using a ready-made bow tie.

10 In accordance with my invention, the fastener 17 is normally retained in complete concealment within the pocket, this being accomplished by making the band 18 of sufficiently short length to retain the hook 17 normally within the confines of the pocket. This prevents the hook from contacting with the neckband of the collar or shirt with which the tie is worn.

15 20 25 In general, it will be understood that changes in the details, herein described and illustrated for the purpose of explaining the nature of my invention, may be made by those skilled in the art without departing from the spirit and scope of the invention as expressed in the appended claims. It is therefore intended that these details be interpreted as illustrative, and not in a limiting sense.

Having thus described my invention, and illus-

trated its use, what I claim as new and desire to secure by Letters Patent is—

1. In a tie having a neckband portion composed of two sections, means for separably joining said sections end to end, comprising complementary fasteners carried by said sections, respectively, an open-end pocket formed on the end of one of said sections, and one of said fasteners being carried within said pocket, the outer wall of said pocket being longer than the inner wall so as to form an extension flap which overlies the area of juncture when the fasteners are connected. 5

2. In a tie having a neckband portion composed of two sections, means for separably joining said sections end to end, comprising complementary fasteners carried by said sections, respectively, an open-end pocket formed on the end of one of said sections, a stretchable band disposed within said pocket and secured at its 20 inner end to the inner end of said pocket, one of said fasteners being carried upon said band, said band in unstretched condition being sufficiently short to retain the fastener within the pocket, and the outer wall of said pocket being longer 25 than the inner wall so as to form an extension flap which overlies the area of juncture when the fasteners are connected. 15

WILLIAM MAYER.
